F. DUTCHER.
RAILWAY SIGNAL TORPEDO.
APPLICATION FILED APR. 25, 1921.

1,402,583.

Patented Jan. 3, 1922.

FIG. 3.

FIG. 4.

Inventor
Frank Dutcher
By
A. J. Pattison,

Attorney

UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL TORPEDO.

1,402,583.

Specification of Letters Patent.

Patented Jan. 3, 1922.

Application filed April 25, 1921. Serial No. 464,111.

To all whom it may concern:

Be it known that I, FRANK DUTCHER, a citizen of the United States, residing at Versailles, in the county of Allegheny and State of Pennsylvania, have invented certain new and useful Improvements in Railway Signal Torpedoes, of which the following is a specification, reference being had therein to the accompanying drawing.

10 This invention relates to improvements in railway signal torpedoes, and more particularly to railway signal torpedoes in which the explosive is carried in telescoping wrappers having crimped ends, the wrappers being provided with a protective casting and the torpedo having means for attaching it to a railway rail.

The primary object of this invention is to provide a railway signal torpedo so constructed that when it is exploded there will be no flying parts or fragments to cause injury or damage.

Another object of this invention is to provide a railway signal torpedo which is simple and cheap of manufacture and highly efficient in use.

A further object of the invention is to provide a simple, cheap and quick manner of attaching the rail-engaging member to the torpedo.

A still further object of my present improvement is to provide a torpedo having a case with a plurality of flat sides so that when it is placed upon a rail and struck by a moving wheel it will not be easily or readily rolled.

Other and further objects and novel features of the invention will appear in the following description and accompanying drawings.

In the accompanying drawings:

Fig. 1 is a perspective view of a torpedo embodying my improved invention, the torpedo being hexagonal in shape.

45 Fig. 2 is a longitudinal vertical sectional view of Fig. 1.

Fig. 3 is a transverse vertical sectional view taken on the line 3—3 of Fig. 2.

50 Fig. 4 is a transverse vertical sectional view through a torpedo embodying my invention, the torpedo being round.

Referring now to the drawings in which like parts are designated by similar reference numerals throughout the description,

1 designates a wrapper of hexagonal shape 55 in cross-section having one extending end 1^a spun or crimped inwardly as at 2. Within the wrapper 1 and retained therein by a paper or other suitable wad 3 is the explosive 4, preferably in loose or powdered form.

The wrapper 5 is also hexagonal of shape in cross-section and of a size to slide over or telescope with the inner wrapper 1, and has its extending end 5^a spun or crimped 65 inwardly as at 6.

With the wrappers 1 and 5 constructed as described, and with the wad 3 abutting the closed end 6 of the outer wrapper 5, as shown in Fig. 2, the powder is confined 70 within a tight container.

To complete the torpedo a rail engaging strap or member 7 is placed upon one of the flat sides of the outer wrapper 5. In the preferable form the strap 7 is of the same 75 width as the flat sides of the wrapper. The wrappers and the rail engaging member are now placed or slid into the protective case 8 which is hexagonal in cross-section. The case 8 is of a proper size to receive the 80 wrappers and explosive snugly and to bind the rail-engaging member firmly in place on the flat side of the wrapper 5 and beneath the case 8.

Fig. 4 shows a torpedo constructed in accordance with the above description with the exception that the case and wrappers are round. In this torpedo 15 and 16 designate the inner and out wrappers and 17 the protective casing. The rail-engaging strap 90 or member 18 is held in place in this instance in like fashion as in the hexagonal shaped torpedo, being clamped between the outer wrapper 16 and the case 17. The explosive charge 19 is contained in the inner 95 wrapper as shown.

I wish it understood that I do not limit myself to any particular shape of torpedo charge, wrapper or case and that other forms of rail-engaging members can be 100 readily and easily adapted to use with my torpedo.

Torpedoes made in accordance with my invention, having telescoping wrappers with their opposite ends crimped and an open 105 ended protective case, do not cause injury by flying particles when they are exploded. When the torpedo is struck by a moving

wheel it starts to mash and the crimped ends are loosened before the explosion occurs. The explosion completes the opening of the crimp, the ends blowing completely open 5 but not off.

If it is desired, the completed torpedo can be given a water-proof bath to protect the explosive from dampness.

Having thus described my invention, what 10 I claim and desire to secure by Letters Patent is:

1. A railway signal torpedo comprising telescoping open ended wrappers having their opposite ends crimped closed and embracing 15 an explosive, an outer open ended case, and a rail-engaging member carried between the case and the wrappers.

2. A railway signal torpedo, comprising telescoping wrappers having a plurality of 20 flat sides, the opposite ends of the wrappers closed, an explosive within the inner wrapper, an outer open ended case embracing the wrappers, and a rail-engaging member carried upon one of the flat sides of the 25 outer wrapper and beneath the case.

3. A railway signal torpedo comprising an explosive within a wrapper having one 30 end crimped inwardly and its other end closed by a wad, an outer wrapper having one end open and embracing the explosive 35 wrapper, the opposite end of the outer wrapper crimped and abutting the wad, an open ended case embracing the two mentioned wrappers, and a rail-engaging member car-

ried by the torpedo between the wrappers 35 and the case.

4. A railway signal torpedo comprising telescoping wrappers having opposite extending ends crimped inwardly, an explosive embraced within the wrappers, a case 40 embracing the wrappers, and a rail-engaging member carried by the torpedo between the wrappers and the case.

5. A railway signal torpedo comprising telescoping wrappers having a plurality of 45 flat sides and provided with oppositely extending ends crimped inwardly, an explosive within the wrappers, a case embracing the wrappers, and a rail-engaging member carried by the torpedo for attaching it to 50 a rail head.

6. A railway signal torpedo comprising telescoping wrappers having a plurality of flat sides and provided with oppositely extending ends crimped inwardly, an explosive 55 within the wrappers, a case embracing the wrappers, and a rail-engaging member carried upon one of the flat sides of the wrapper and beneath the case.

7. A railway signal torpedo comprising 60 an explosive carried within wrappers having oppositely crimped ends, a case embracing the explosive and its wrappers, and a rail engaging member carried by the torpedo for attaching it to a rail-head.

In testimony whereof I hereunto affix my signature.

FRANK DUTCHER.
